HAIR CURLER

Jingo Natsukawa, 1904 Oaza Maibara, Sakata-gun,
Shiga Prefecture, Sakata-gun, Japan

Filed Dec. 18, 1963, Ser. No. 77,849

Term of patent 14 years

(Cl. D86—10)

FIG 1

FIG 6

FIG. 1 is an end elevational view of a hair curler showing my new design;

FIG. 2 is a side elevational view thereof;

FIG. 3 is a perspective view thereof;

FIG. 4 is an end elevational view of the hair curler shown in FIG. 1, wherein the flexible loops are cut at their summit;

FIG. 5 is a side elevational view thereof; and

FIG. 6 is a perspective view thereof.

I claim:

The ornamental design for a hair curler, as shown and described.
